UNITED STATES PATENT OFFICE

PARK B. HYDE, OF OAKLAND, CALIFORNIA, ASSIGNOR TO NATIONAL RAILWAY SIGNAL COMPANY, OF RENO, NEVADA, A CORPORATION OF NEVADA

RAILWAY-SIGNALING SYSTEM

Application filed February 20, 1929. Serial No. 341,375.

This invention relates generally to systems for use at railway crossings for indicating the presence or approach of trains.

With present-day signaling systems for use with highway crossings, accidents are a frequent occurrence due to the fact that only a single indication is employed to warn of the approach of trains, regardless of the number of trains. For example a person approaching upon the highway may see a train standing or moving slowly toward the crossing on one track and believe that the crossing is safe, while in reality another unobserved train is approaching on the other track from a different direction. It may also happen that a train which has just cleared the crossing obstructs the view of the other track upon which another train is approaching in a different direction, thus misleading one to believe that the crossing is safe. Thus even though the crossing signal may be operating properly, it may not give warning that an attempted crossing is dangerous.

It is an object of this invention to devise a signaling system of the above character which will give adequate warning at a highway crossing over railway tracks.

It is a further object of this invention to devise a railway signaling system of this character which will effect one indication at a crossing upon the approach of a single train, and will give another different indication when two or more trains are approaching.

It is a further object of this invention to devise a railway signaling system which will make possible a separate characteristic indication at a crossing when one train has just cleared the crossing but is adjacent thereto and another train is approaching the crossing.

It is a further object of this invention to devise a signaling system which will effect a characteristic indication when two or more trains are approaching towards a crossing, and which is provided with means whereby the indication is continued after being set in operation until the last of two or more trains have cleared the operating zone.

It is a further object of this invention to

devise a novel and effective arrangement of electrical circuits for the control and operation of highway signals.

Further objects of the invention will appear from the following description in which I have set forth the preferred embodiments of my invention. It is to be understood that the appended claims are to be accorded a range of equivalents consistent with the state of the prior art.

Referring to the drawing:

Figure 1 is a perspective view illustrating my signaling system applied to a railway crossing.

Fig. 2 is a side elevational view of signal devices which can be utilized in my system.

Fig. 3 is a front view of the signal devices shown in Fig. 2.

Fig. 4 is a circuit diagram illustrating one form of the circuit connections incorporating the system of my invention.

Fig. 5 is a circuit diagram illustrating a modified form of system.

The preferred embodiments of my invention shown in the drawing can be described in detail as follows: In Fig. 1 there is shown a typical railway crossing in which the highway 10 crosses a plurality of parallel tracks 11 and 12. Arranged at or near the crossing so as to attract the attention of persons approaching along the highway, are the signaling devices 13 and 14, these devices being suitably mounted as by means of posts 16. Generally duplicate signaling devices are provided upon each side of the crossing as shown, so that their effectiveness is not precluded by obstruction of the track.

As has been previously mentioned, in my system I utilize two distinct indications, and the signaling devices 13 and 14 provide convenient means for effecting this result. By indication I have reference to any effective warning such as can be produced by a sounding device, or by a visual display. For example in Figs. 2 and 3 I have shown a signaling device 13 consisting of an electric lamp 17 in conjunction with an electrical gong. Lamp 17 is positioned behind a suitable colored stencil 19 lettered to read "Two trains". Device 14 can consist of an electrical gong 100

having a tone different from the gong of device 13. While devices of this character are satisfactory for producing two distinct indications, it is obvious that the indications can be otherwise produced and characterized.

5 For example one indication may be a light while the other is a sound, different sounds can be employed, or an illuminated or sound indication can be employed together with a 10 waving or recurrently moving display.

10 Referring now to Fig. 4, I prefer to provide electrical means for controlling and actuating the signal devices 13 and 14. Thus I have shown each of the tracks 11 and 12 divided 15 into a plurality of zones in the vicinity of the crossing. Zone A of each track is positioned a sufficient distance from the crossing to provide an adequate lapse of time from the instant a train enters this zone to the time it 20 passes over the crossing, and each zone terminates just beyond the crossing. A second zone B is provided for each track, this zone being preferably of lesser extent than zone A and being in position to be transversed by 25 a train after zone A has been cleared. As is common practice in railway signaling systems, these zones can be formed by including the rails of the track in an electrical circuit, the ends of the rails corresponding to the 30 ends of the zones being insulated from the adjoining rails as indicated at 21.

35 The control circuit and associated relays which I have employed in conjunction with the above zones, can be described in detail as follows: The rails of zone A of track 11 are connected to the winding of a relay 22, while the corresponding rails of track 12 are connected to the windings of a relay 23. The rails of zone B of track 11 are connected to 40 the winding of a relay 26, while the corresponding rails of track 12 are connected to the winding of a relay 27. Batteries 28 are connected across the rails of the different zones for energizing the windings of these 45 relays, and when these batteries are shorted by the wheels and trucks of a train, the corresponding relay is deenergized to drop its armature. For convenience I have shown devices 13 and also devices 14 connected together in parallel. Thus conductors 31 and 50 32 serve to connect in parallel devices 13, while conductors 33 and 34 similarly connect together devices 14. A local source of current such as battery 36 has its one terminal 55 connected to conductor 34 by way of wire or conductor 37, and also to conductor 32 by way of conductor 38.

60 The contacts of relays 22, 23, 26 and 27 are interrelated to effect the desired mode of operation which will be presently described. Thus armatures 41 and 42 of relays 22 and 26 are connected together and to conductor 43, while conductor 43 connects together contacts 44 and 46 of relays 23 and 27 respectively. Armatures 47 and 48 of relays 23

and 27 respectively are both connected to conductor 49, which in turn is connected to conductor 31 interconnecting devices 13. Relay 22 is preferably provided with an auxiliary armature 51 and cooperating contact 52 while 70 relay 23 is similarly provided with an armature 53 and contact 54. Contacts 52 and 54 are both connected by conductor 56 to the other terminal of battery 36. Armatures 51 and 53 are both connected to conductor 57 75 which in turn is connected to conductor 33, by conductor 58. Contacts 59 and 61 of relays 22 and 26 respectively are also both connected to conductor 57.

To explain the mode of operation of the 80 arrangement shown in Fig. 4, it will be presumed that a train is approaching the crossing on track 11 and that it is entering zone A. Since the rails of the track are short circuited, relay 22 is deenergized to drop its armature 41 and close contact 59. Likewise armature 51 is dropped to close contact 52. An energizing circuit is thereby completed from battery 36 to device 14, which can be traced as follows: from battery 36, conductor 37, 85 thru devices 14, conductor 58, conductor 57, armature 51 and contact 52, and conductor 56 back to battery 36. Devices 14 are therefore actuated to produce an indication which warns persons on the highway of the approach of a train. When the train has cleared the highway and zone A, its presence on zone B causes the winding of relay 26 to be deenergized, while relay 22 is again 90 energized. The closing of armature 42 upon contact 61 cannot of itself complete an energizing circuit to either of the signaling devices 13 and 14, so that these devices are not actuated under such conditions. Similarly if a train approaches in a different direction 100 along track 12, as it enters zone A relay 23 is deenergized to complete the same energizing circuit for signaling devices 14 thru armature 53 and contact 54.

105 As a second possible condition it is presumed that two trains are approaching the crossing at about the same time. If these trains are both present on zones A of tracks 11 and 12 at the same time, both relays 22 and 23 are deenergized. Signaling devices 14 are again actuated because of the completion of the energizing circuit previously traced. Another energizing circuit however is completed from battery 36 to the signaling devices 13, so that another and different indication is effected. This circuit can be traced as follows: from battery 36, by way of conductor 38, conductor 32, thru devices 13, conductor 31, conductor 49, armature 47 and contact 44 of relay 23, conductor 43, armature 41 and contact 59 of relay 22, armature 51 and contact 52 of relay 22, and conductor 56 back to battery 36. If both trains clear the 110 crossing at about the same time and are present upon zones B at the same time, relays 115 120

22 and 23 will again pick up their armatures and relays 26 and 27 will be deenergized. However deenergization of relays 26 and 27 alone cannot complete an energizing circuit 5 to the signaling devices, so that no indication will be given for this condition.

As a third possible condition it is presumed that a train on track 11 has cleared the crossing but is still occupying zone B, 10 while a train is approaching on the other track and has entered zone A. The train entering zone A of track 12 might not be observed by persons approaching on the highway, particularly since their view might 15 be obstructed by the train within zone B. Seeing a train headed away from the highway one would naturally expect a crossing to be safe. To produce a characteristic indication by operation of devices 13 to warn 20 of this condition, deenergization of relays 26 and 23 likewise serves to complete an energizing circuit for devices 13 while deenergization of relay 23 effects actuation of devices 14 as has been previously described. 25 The energizing circuit for devices 13 at this time can be traced as follows: from battery 36 by way of conductor 38, conductor 32, thru devices 13, conductor 31, conductor 49, armature 47 and contact 44 of relay 23, conductor 43, thru armature 42 and contact 61 of relay 26, conductor 57, thru armature 53 and contact 54 of relay 23, conductor 56 back to battery 36. If the condition is reversed and a train on track 12 has cleared 30 zone A but is present in zone B, and a train is entering zone A of track 11 from a different direction, relays 22 and 27 are deenergized to complete a circuit in the same manner for signaling devices 13, while deenergization of relay 22 alone effects actuation of 35 devices 14 as has been previously described.

It is apparent from the above description that my system will provide adequate warning so that a person is definitely apprised 40 of the fact that a crossing is safe. The presence of one or more trains which have apparently cleared the crossing cannot mislead one into making a dangerous crossing when devices 13 are producing a characteristic indication.

In order to provide an added factor of safety, the system of Fig. 4 can be modified to the extent of providing means for continuing actuation of signaling devices 13 55 until the last of two or more trains have cleared the approaching zones. Such an arrangement is shown in Fig. 5 in which in addition to relays 22, 23, 26 and 27, I provide a stick magnetic relay 66. Relay 66 has two armatures 67 and 68 which cooperate 60 respectively with contacts 69 and 71. Armatures 47 and 48 of relays 23 and 27 respectively in this case are both connected 65 to conductor 72, which in turn is connected to one side of the winding of relay 66 and

to armature 67. Contact 69 is connected to conductor 57, and contact 71 is connected to conductor 56. The other side of the winding of relay 66 is connected to battery 36 by way of conductor 38.

To explain the mode of operation of the circuit arrangement shown in Fig. 5, it is presumed that a train has been present in one of zones A, say that of track 11, at the same time that a train has been present in zone B of track 12. As has been previously explained, under such conditions both signaling devices 13 and 14 are actuated. However with the arrangement of Fig. 4, when zone B is cleared and only zone A is being occupied, signaling devices 13 are no longer actuated, but devices 14 are operated in the same manner as when warning of the approach of a single train. With the arrangement of Fig. 5 when both zones A and B are occupied simultaneously, the two corresponding relays, for example relays 22 and 27 are deenergized. Deenergization of these relays however results in the completion of an energizing circuit to the winding of relay 66 which can be traced as follows: from battery 36 thru conductor 38, the winding of relay 66, conductor 72, armature 48 and contact 46 of relay 27, conductor 43, armature 41 and contact 59 of relay 22, armature 51 and contact 52 of the same relay, and thru conductor 56 back to battery 36 in the same manner as in Fig. 4. Now when zone B of track 12 is cleared before the clearing of zone A of track 11, relay 27 is energized while relay 22 continues to be deenergized. However since the armatures 67 and 68 of relay 66 are closed at this time, the winding of this relay continues to be energized. This energizing circuit can be traced from battery 36, thru conductor 38, winding 66, conductor 72, armature 67 and contact 69 of relay 66, conductor 57, armature 51 and contact 52 of relay 22, and conductor 56 back to battery 36. Energization of relay 27 while relay 66 remains energized does not result in deenergization of signaling devices 13, since a circuit is still completed to these devices and can be traced as follows: from battery 36, thru conductor 38, conductor 32, thru devices 13, conductor 31, conductor 74, armature 68 and contact 71 of relay 66, conductor 56 back to battery 36.

When zone A as well as zone B has been cleared by the last train, relay 22 is again energized, and in picking up its armature 51, the holding or energizing circuit to the winding of relay 66 is interrupted, thus causing this relay to drop its armatures. Signaling devices 13 are therefore deenergized, and devices 14 are likewise deenergized directly by energization of relay 22 as has been previously explained.

It is apparent that the circuit arrangements of Figs. 4 and 5 can be greatly modified within the scope of this invention. Track instruments or contacts can be sub-

stituted in place of track circuits, or various arrangements or types of relays can be employed. Furthermore by readily made modifications the system can be used on a single track where the crossing is near the switch at the end of a siding or stretch of double track, so that trains may meet or pass over the crossing in opposite directions in close succession; or to protect a crossing where one train may closely follow another on the same track.

10 I claim:

1. A railway signaling system for a highway crossing, comprising means for effecting an indication at the crossing responsive to the approach of a single train, and means for effecting a different indication at the crossing responsive to the approach of a plurality of trains, said different indication having characteristics other than the characteristics 15 of the indication effected by and responsive to the approach of a single train.

2. A railway signaling system for a crossing over a plurality of tracks, comprising means for effecting an indication at the crossing responsive to the approach of a train on any one of said tracks, and other means for effecting a different indication at the crossing responsive to the approach of a plurality of trains.

3. A railway signaling system for a highway crossing, comprising means for effecting an indication at the crossing responsive to the approach of a single train, and other means for effecting a different indication at the crossing responsive to and characteristic only of the presence of another train near the crossing while the first-named train is approaching.

4. A railway signaling system for a highway crossing, comprising means for effecting an indication at the crossing responsive to the approach of a single train, and means for effecting a different indication at the crossing responsive to the presence of another train which has cleared the crossing but is adjacent the same while the first-named train is approaching.

5. A railway signaling system for a highway crossing, comprising means for effecting an indication at the crossing responsive to the approach of a single train, and means for effecting a different indication at the crossing responsive either to the approach of a plurality of trains or to the presence of one or more trains which have cleared the crossing but are adjacent to the same while one or more other trains are approaching.

6. A railway signaling system for a highway crossing, comprising means for effecting an indication at the crossing responsive to the approach of a single train, means for effecting a different indication at the crossing responsive to the presence of another train near the crossing while the first-named train is approaching, and means for continuing said

different indication after it is initiated so long as a train is approaching the crossing.

7. A railway signaling system for a highway crossing, comprising means for effecting an indication at the crossing responsive to the approach of a single train, means for effecting a different indication at the crossing responsive to the presence of another train which has cleared the crossing but is adjacent the same while the first-named train is approaching, and means for continuing said different indication after it is initiated so long as a train is approaching the crossing.

8. A railway signaling system for a highway crossing, comprising means for effecting an indication at the crossing responsive to the approach of a single train, means for effecting a different indication at the crossing responsive either to the approach of a plurality of trains or to the presence of one or more trains which have cleared the crossing but are adjacent to the same while one or more other trains are approaching, and means for continuing said different indication after it is initiated so long as a train is approaching the crossing.

9. In a railway signaling system for a highway crossing over a pair of parallel tracks, a first signaling zone on each track near the crossing, a second signaling zone on each track, means for effecting an indication at the crossing responsive to the presence of a train on either one of said first signaling zones, and means for effecting a different indication at the crossing responsive to the presence of trains in both said first zones or to the presence of trains in the first and second zones of different tracks.

10. In a railway signaling system for a highway crossing over a pair of parallel tracks, a first signaling zone on each track near the crossing, a second signaling zone on each track, means for effecting an indication at the crossing responsive to the presence of a train on either one of said first signaling zones, and means for effecting a different indication responsive to the presence of trains in both said first zones or to the presence of trains in the first and second zones of different tracks, and means for continuing said different indication after it is initiated until the first zones have been cleared.

11. In a railway signaling system for a highway crossing over a plurality of tracks, a signal for the highway, a track circuit on the portion of each track traversed by the trains approaching the highway, a relay included in each circuit adapted to be deenergized by a train on the corresponding track portion, a control circuit for said signal arranged to effect operation of the signals during deenergization of the relay on any one of said track circuits, an auxiliary signal for the highway, a track circuit on each track beyond the highway and a control circuit for said

auxiliary signal arranged to effect display of the auxiliary signal during deenergization of the relay on any one of said first named track circuits when the relay on either track circuit on any other track is deenergized.

5 12. In a railway signaling system for a highway crossing over a plurality of tracks, a signal for the highway, a track circuit on the portion of each track traversed by trains approaching the highway, a relay included in each circuit adapted to be deenergized by a train on the corresponding track portion, a control circuit for said signal arranged to effect operation of the signal during deener-

10 gization of the relay on any one of said track circuits, an auxiliary signal for the highway, a track circuit on each track beyond the highway, a control circuit for said auxiliary signal arranged to effect operation of the auxil-

15 iary signal during deenergization of the relay on any one of said first named track circuits when a relay on either track circuit on any other track is deenergized, and means whereby said last named control circuit is

20 maintained in signaling operating condition so long as the relay on any one of said first named track circuits is deenergized.

25

In testimony whereof, I have hereunto set my hand.
